UNITED STATES PATENT OFFICE.

WILLIAM A. SCHRAUBSTADTER, OF ST. LOUIS, MISSOURI.

DESIGN FOR A FONT OF TYPE.

40,718.

Specification for Design.

Patented May 31, 1910.

Application filed May 13, 1909. Serial No. 495,829. Term of patent 14 years.

To all whom it may concern:

Be it known that I, WILLIAM A. SCHRAUBSTADTER, a citizen of the United States, and a resident of the city of St. Louis and State of Missouri, have invented a new, original, and ornamental Design for a Font of Type, of which the following is a specification.

My design consists in the features shown in the accompanying drawing which forms part of this specification.

I claim:

The ornamental design for a font of type as shown.

WILLIAM A. SCHRAUBSTADTER.

In the presence of—

E. A. DEHN,
J. M. DURDY.
